Primary Examiner—Dominic Simone(74) Attorney, Agent, or Firm—Banner & Witcoff, Ltd.(57) CLAIM

The ornamental design for a portion of a shoe upper, as shown and described.

DESCRIPTION

FIG. 1 is a front perspective view of a portion of a shoe upper showing my new design;

FIG. 2 is a rear perspective view thereof; and,

FIG. 3 is a side view thereof.

The uneven broken line showing immediately adjacent to the shaded area represents an unclaimed boundary of the design. The uneven broken showing the remainder of the shoe, are for illustrative purposes only and form no part of the claimed design.
